DAY BED WITH CANOPY

Henry Olko, Applegreen Drive,
Old Westbury, N.Y. 11568

Filed Aug. 23, 1974, Ser. No. 499,979

Term of patent 14 years

Int. Cl. D6—01

U.S. Cl. D6—59

Fig. 1

Fig. 2

Fig. 4

Fig. 3

Fig. 5

FIG. 1 is a front view of a day bed with canopy embodying my design;

FIG. 2 is a top view of the day bed with canopy of FIG. 1;

FIG. 3 is a side view of the day bed with canopy of FIGS. 1 and 2;

FIG. 4 is a back view of the day bed with canopy of FIGS. 1, 2 and 3; and,

FIG. 5 is a front perspective view of the embodiment of FIGS. 1 to 4.

I claim:

The ornamental design for the day bed with canopy, as shown.
